UNITED STATES PATENT OFFICE.

TOM HARPER, OF COLUMBIA, MISSISSIPPI.

WELL-BUCKET.

1,378,450.

Specification of Letters Patent. Patented May 17, 1921.

Application filed May 21, 1920. Serial No. 383,270.

To all whom it may concern:

Be it known that I, TOM HARPER, a citizen of the United States, residing at Columbia, in the county of Marion and State 5 of Mississippi, have invented a new and useful Well-Bucket, of which the following is a specification.

The present invention aims to provide an improved well bucket which is so constructed that the valve in the bottom of the same may be removed readily and a new one inserted.

In the drawing Figure 1 is a vertical sectional view of my improved well bucket;

15 Fig. 2 is a bottom plan of the same;

Fig. 3 is a top plan of the removable valve seat and valve.

Referring to the drawing, the numeral 5 denotes a well bucket which has its upper 20 end open the bucket being provided with a bail 6 to which the well rope is adapted to be secured.

The bottom of the bucket is designated at 7 and is provided with a central opening 8 having interior screw threads 9. A removable valve seat 10 is provided and has screw threads 11 upon its periphery which are engaged with the threads 9 in the opening 8. The valve seat 10 is provided with a 30 central opening or port 12 and is further provided with recesses or notches 13 at diametrically opposite points, at the edge of the opening, and upon the outer face of the valve seat, these recesses being adapted to receive a tool, whereby the valve may be threaded readily into the opening 8 or be 45 disengaged therefrom.

A check valve 14 in the form of a flap is secured to the inner face of the valve seat 40 10 by a staple 25 or the like and normally covers the opening 12. The valve 14 is adapted to open inwardly to permit the ingress of water when the bucket is lowered into the well.

It will be manifest that I have provided 45 a simple and inexpensive bucket embodying a construction which will permit the valve to be removed from the bottom of the bucket, for renewal or repair.

What I claim as new and desire to protect 50 by Letters Patent is:—

1. In a well bucket, a cylindrical body having its upper end open and provided with a central opening in its bottom, the opening having interior screw threads, a 55 valve seat threaded into the opening, and a flap valve secured to the inner face of the valve seat.

2. In a well bucket, a cylindrical body having an opening in its bottom, a valve seat threaded in the opening and provided with an inlet, and with notches at diametrically opposite points for the reception of a tool, thereby to engage and disengage the valve seat from the bottom, and a flap valve 60 secured to the inner face of the valve seat 65 normally closing the inlet.

3. In a well bucket, a cylindrical body having a central threaded opening in its bottom, a valve seat threaded into the opening and provided with an inlet port, and with notches at diametrically opposite points at the edge of the inlet port, the notches being adapted to receive a tool thereby to 70 thread the valve seat into and out of the opening, and a flap valve secured to the inner face of the valve seat and normally closing the inlet port. 75

In testimony that I claim the foregoing as my own, I have hereto affixed my signature in the presence of two witnesses.

TOM HARPER.
